US0D1084711S

(12) **United States Design Patent** (10) **Patent No.:** **US D1,084,711 S**
(45) **Date of Patent:** **** Jul. 22, 2025**

(54) **CABINET**

(71) Applicant: **Yahee Trading Limited**, Hong Kong (CN)

(72) Inventor: **Le Yang**, Hong Kong (CN)

(73) Assignee: **Yahee Trading Limited**, Hong Kong (CN)

(*) Notice: Patent file contains an affidavit/declaration under 37 CFR 1.130(b).

(**) Term: **15 Years**

(21) Appl. No.: **29/896,909**

(22) Filed: **Jul. 10, 2023**

(30) **Foreign Application Priority Data**

Apr. 21, 2023 (CN) 202330225477.X

(51) **LOC (15) Cl.** **06-04**

(52) **U.S. Cl.**

USPC **D6/657**; D6/662

(58) **Field of Classification Search**

USPC D6/329, 559, 561, 648.2, 648.3, 653,

D6/653.1, 654, 654.1, 657, 659, 660, 661,

D6/662, 663, 671, 672, 675, 691, 705;

(57) **CLAIM**

The ornamental design for a cabinet, as shown and described.

DESCRIPTION

FIG. 1 is a top front right perspective view of a cabinet showing my new design;

FIG. 2 is a bottom back left perspective view of the cabinet;

FIG. 3 is a front elevational view of the cabinet;

FIG. 4 is a rear elevational view of the cabinet;

FIG. 5 is a left side view of the cabinet;

FIG. 6 is a right side view of the cabinet;

FIG. 7 is a top plan view of the cabinet; and,

FIG. 8 is a bottom plan view of the cabinet.

The broken lines illustrate portions of the cabinet and form no part of the claimed design.

1 Claim, 8 Drawing Sheets
